UNITED STATES PATENT OFFICE.

FRANK D. JACOBS, OF CANTON, MASSACHUSETTS.

PENCIL.

No. 847,579.

Specification of Letters Patent. Patented March 19, 1907.

Application filed June 28, 1906. Serial No. 323,837.

To all whom it may concern:

Be it known that I, FRANK D. JACOBS, a citizen of the United States, residing in Canton, in the county of Norfolk and State of Massachusetts, have invented an Improvement in Pencils, of which the following description, in connection with the accompanying drawings, is a specification, like letters on the drawings representing like parts.

This invention relates to a lead-pencil, and has for its object to provide a pencil angular in cross-section with means for preventing slipping of the pencil either in the hand or in the pocket of the user, which result is obtained without interfering with the plain surfaces upon which the name of the maker or other advertising matter is printed or otherwise affixed. For this purpose the lead-pencil, which is angular in cross-section and may be triangular, square, hexagon, or of other than round shape in cross-section, is provided on the meeting edge of adjacent facets or surfaces with indentations or serrations which form roughened edges, which serve to prevent slipping of the pencil either in the hand or pocket of the user. The indentations or serrations extend transversely of the pencil and are made substantially short, so as to leave the facets or surfaces of the pencil substantially unimpaired and available for printing or otherwise marking advertisements on the pencil.

The drawing represents a pencil embodying this invention.

Referring to the drawing, *a* represents a lead-pencil of angular shape in cross-section to form facets *b*, which extend longitudinally of the pencil. In the present instance the pencil *a* is shown as hexagonal in cross-section. The faceted surfaces *b* are designed to have printed upon or otherwise applied to them suitable advertisements. One such advertisement is shown, consisting of the number "582," the representation of an eagle, and the words "Eagle Noblesse No. 2."

The present invention has for its object to provide the pencil *a* with means for prevent-

ing it slipping either in the hand or the pocket of the user without impairing or interfering with the advertisements on the 50 faceted surfaces. For this purpose the longitudinal ridges or edges *d* formed by adjacent facets are provided with substantially short transverse indentations or serrations *e*, which are arranged substantially the length 55 of the pencil and which are so short as not to extend into the faceted surfaces for any material distance, thereby leaving said faceted surfaces substantially unmarked or unimpaired by the indentations and in condition 60 for substantially their full width to receive the advertisement thereon.

The indentations or serrations *e* may be formed by a suitable die or tool, so as to insure them being of uniform length and so as 65 not to extend into the faceted surface for any material distance. In this manner a lead-pencil of angular cross-section is provided which is not liable to slip out of the pocket or in the hand of the user, while at the same 70 time the faceted surfaces for substantially their full width are preserved for the advertisements, which in this manner are not rendered more or less illegible as would be the case if the indentations extended across the 75 faceted surfaces for any material distance.

I claim—

As an improved article of manufacture, a lead-pencil angular in cross-section to form longitudinally-extended faceted surfaces, and having indentations or serrations extended across the meeting edges of adjacent faceted surfaces substantially at right angles thereto and on opposite sides thereof, said indentations or serrations extending but partially 85 across said faceted surfaces.

In testimony whereof I have signed my name to this specification in the presence of two subscribing witnesses.

FRANK D. JACOBS.
